UNITED STATES PATENT OFFICE.

FERDINAND PAVEL, OF NEW YORK, N. Y.

DESIGN FOR A PORTABLE ELECTRIC LAMP.

Application filed September 15, 1927. Serial No. 23,429. Term of patent 7 years.

To all whom it may concern:

Be it known that I, FERDINAND PAVEL, a citizen of the United States residing at New York, in the county of New York and State of New York, have invented a new, original, and ornamental Design for a Portable Electric Lamp, reference being had to the accompanying drawing, forming part thereof.

Fig. 1 is a side view of a portable electric lamp showing my new design.

Fig. 2 is a plan view of a portable electric lamp showing my new design.

I claim:

The ornamental design for a portable electric lamp as shown.

In testimony whereof I have affixed my signature.

FERDINAND PAVEL.
